UNITED STATES PATENT OFFICE.

JOSEPH F. BATCHELOR, OF BALTIMORE, MARYLAND.

SIGNAL-LANTERN.

SPECIFICATION forming part of Letters Patent No. 230,522, dated July 27, 1880.

Application filed May 14, 1880. (No model.)

To all whom it may concern:

Be it known that I, JOSEPH F. BATCHELOR, a citizen of the United States, residing at Baltimore, in the county of Baltimore and State of Maryland, have invented certain new and useful Improvements in Signal-Lanterns; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain improvements in hand-lanterns such as are used by train-men and station-agents on railroads, the object of my invention being to provide means combined within an ordinary lantern whereby 20 the latter may be convertible, when desired, into a signal-lantern, as hereinafter fully described.

25 In the drawings hereto annexed, Figure 1 is an elevation, partly in section, of a lantern embodying my improvements. Fig. 2 is a horizontal section of the lantern as seen through the line *x x* in Fig. 1. Fig. 3 is a side view of the signal-glass and guide-wires. Fig. 4 is a plan or top view of the same.

30 The letter A designates the oil-fount, which is detachable through the base or bottom in the usual manner. B is the globe, and C the wire frame or guard surrounding the globe.

The dome or top part, E, is made in any 35 suitable manner, so as to be separable from the frame. It may, for instance, be hinged at one side, as shown at *d*.

Four wires, *f*, are each attached by one end to the inner side of the base part G, and extend vertically upward through the globe and into the dome, their upper ends being connected by a wire ring, *h*. Just above the base or the oil-fount the four wires pass through an annular plate, *i*, to which they are secured.

40 A portion of this plate projects inward, and serves as a seat or base on which the straight chimney *n* rests. The portion of this plate which projects outward serves as a rest or base for the signal-glass L.

45 It will be seen that the guide-wires *f* serve in a twofold capacity—first, as a frame which

surrounds and retains the straight chimney, and, second, as a guide on which the signal-glass will slide up and down.

The signal-glass, as shown in Fig. 4, consists of a semi-cylindrical glass plate having on each side a small metallic plate, *p*, provided with a lateral projecting eye, *q*, which slides on the guide-wire. A chain, *r*, is attached to each small plate which has the eye, 55 and said chains extend up through the top *s* of the dome above, and on the outside of which the chains are connected in any suitable manner, and preferably are provided with a ring or equivalent device, *t*. 60

65 It will be seen that the signal-glass may be raised from the annular plate *i* up into the dome by drawing on the chains, and when so raised may be retained in the elevated position by engaging the ring *t* with the hook *u*, 70 (see Fig. 2,) which is secured to the outside wire frame.

A modification of the signal-glass consists in making it in the form of a cylinder, which will entirely surround the four guide-wires and 75 the chimney. The operation of raising or lowering it by means of the guide-wires and chains in either case is the same. The semi-cylindrical form of signal-glass, however, has the advantage of permitting the use of two 80 signals, each of a different color—as, for instance, a red glass may be employed on one side and to slide on two of the guide-wires, while a green or blue glass may in like manner be employed on the other side. 85

The bail or handle of the lantern is represented in Fig. 1 by the letter *v*, and as broken off.

The chimney and the globe are both to be placed in position, should either be broken, 90 by the removal of the dome part, the chimney being entered endwise through the ring *h*.

The advantages of an ordinary hand-lantern convertible at pleasure into a signal-lantern are so obvious as not to need enumeration here. 95

Having described my invention, I claim and desire to secure by Letters Patent of the United States—

1. In a lantern, the combination of guide-wires secured to the lamp-base and extending vertically through the globe, and an annular

plate secured to the wires just above base and projecting inward to form a seat for the chimney, as set forth.

2. The combination, as set forth, of guide-wires secured to the lamp-base and extending vertically through the globe, a chimney which is retained in position by the said wires, and a seat for the chimney independent of the oil-fount, whereby the oil-fount may be detached through the base without disturbing the chimney.

3. The combination, as set forth, of guide-

wires secured to the lamp-base and extending vertically through the globe, a chimney which is retained in position by the said wires, a seat for the chimney independent of the oil-fount, and a signal-glass adapted to slide up and down on the wires. 15

In testimony whereof I affix my signature in presence of two witnesses.

JOSEPH F. BATCHELOR.
